PACKAGING CONTAINER FOR FOOD OR THE LIKE

Stephen W. Amberg, St. James, N.Y., assignor to Lily-Tulip Cup Corporation, New York, N.Y., a corporation of Delaware

Continuation of design applications Ser. No. 5,124 and Ser. No. 5,125, Dec. 20, 1966. This application Sept. 13, 1967, Ser. No. 8,799

Term of patent 14 years

(Cl. D9—219)

This application is a continuation of applications Ser. Nos. D. 5,124 and D. 5,125 both filed Dec. 20, 1966 and now abandoned.

I claim:

The ornamental design for a packaging container for food or the like, substantially as shown and described.
